Attorney

UNITED STATES PATENT OFFICE

JOHN E. OSTRANDER, OF STAATSBURG, NEW YORK

ICE CREEPER

Application filed December 11, 1930. Serial No. 501,647.

This invention relates to ice creepers and the invention has for an object to provide a device of this kind which is adapted for wear under both the sole portion and heel portion of a boot or shoe.

It is also an object of the invention to provide a device of this kind wherein the two portions of the creeper are so connected as to provide a unitary structure and in a manner to assure the maintenance of the device in effective working placement.

The invention consists in the details of construction and in the combination and arrangement of the several parts of my improved ice creeper whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in side elevation of an ice creeper constructed in accordance with an embodiment of my invention;

Figure 2 is a view in top plan of the device as illustrated in Figure 1;

Figure 3 is a fragmentary sectional view taken substantially on the line 3—3 of Figure 1.

As disclosed in the accompanying drawings, T denotes a toggle member adapted to underlie the sole portion of a boot or shoe and wherein the connecting members 1 for the levers 2 of the toggle are extended to constitute calks.

The forward levers 2 of the toggle member T have pivotally connected thereto substantially midway their ends the outwardly disposed and relatively short arms 3, the connecting members 4 also constituting calks.

The rear levers 2 of the member T substantially midway their ends are provided with the further calks 5.

The outer ends of the arms 3 extend upwardly, as at 6, to overlie the side portions of a boot or shoe and pivotally connected to

said upstanding portions 6 are the eye members 7 through which are freely directed a holding strap 8, said strap being adapted to be disposed over the toe portion of the boot or shoe.

55

The members 9 for pivotally connecting the eye members 7 also serve as pivots for the forward end portions of the elongated side bars 10, the opposite or rear end portions of which being pivotally connected by the members 11 with the upstanding side arms 12 provided at the outer ends of the plates 14. The members 11 also serve as pivots for the upstanding eye or loop members 15 through which is freely directed a strap 16. The forward portion of the strap 16 between the eye or loop members 15 is freely engaged with a rearwardly disposed hook or clip member 17 pivotally connected with the rear portion of the toggle member T. This portion 70 of the strap 16 is adapted to extend across and below the arch portion of the boot or shoe with which the creeper in its entirety may be employed. The strap 16 is also adapted to be disposed and engaged over the instep of the footwear with the free end portions of the strap connected in any desired manner.

75

The plates 14 are adapted to underlie the heel of a boot or shoe while the arms 12 are arranged at the sides of the footwear closely adjacent to the forward end of the heel proper. The upper end portions of the arms 14 are connected by an elongated spring strip 18 which, when the device is applied, snugly 85 straddles from the rear the heel portion of the footwear.

By properly tightening the straps 8 and 16 the device will be caused to properly adjust itself to the sole and heel portions of the footwear to which it is applied, thus assuring the device being held in desired working position.

The plates 14 have depending therefrom 95 desired calks 19.

It is to be stated that the levers 2 of the toggle member T possess sufficient inherent resiliency or flexibility to allow the same to readily conform to the portion of the sole 100

of a boot or shoe with which said toggle member is associated.

It is also believed to be apparent from the foregoing description that the assembly of the various parts and especially as afforded by the various pivotal connections, allows the device in its entirety to substantially instantaneously adjust itself to various sizes of boots or shoes as a result of drawing strain 16 upon the straps 8 and 16.

From the foregoing description it is thought to be obvious that an ice creeper constructed in accordance with my invention is particularly well adapted for use by reason 15 of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying 20 out my invention in practice except as hereinafter claimed.

I claim:—

1. An ice creeper of the class described comprising a member adapted to underlie the sole portion of a boot or shoe, a member adapted to underlie the heel portion of such footwear, both of said members having parts extending up on the opposite sides of the footwear and including means for laterally adjusting said members, side members connecting said parts, retaining means coacting with the upstanding parts of the sole member, and retaining means coacting with the upstanding parts of the heel member.

2. An ice creeper of the class described comprising a member adapted to underlie the sole portion of a boot or shoe, a member adapted to underlie the heel portion of such footwear, both of said members having parts extending up on the opposite sides of the footwear and including means for laterally adjusting said members, side members connecting said parts, retaining means coacting with the upstanding parts of the sole member, and retaining means coacting with the upstanding parts of the heel member, said last named retaining means being also engaged with the sole member.

3. An ice creeper of the class described comprising a member adapted to underlie the sole portion of a boot or shoe, a member adapted to underlie the heel portion of such footwear, both of said members having parts extending up on the opposite sides of the footwear and including means for laterally adjusting said members, side members connecting said parts, retaining means coacting with the upstanding parts of the sole member, and retaining means coacting with the upstanding parts of the heel member, said last named retaining means being also engaged

with the sole member, said sole member constituting a toggle structure.

4. An ice creeper of the class described comprising a member adapted to underlie the sole portion of a boot or shoe, a member adapted to underlie the heel portion of such footwear, both of said members having parts extending up on the opposite sides of the footwear and including means for laterally adjusting said members, side members connecting said parts, retaining means coacting with the upstanding parts of the sole member, and retaining means coacting with the upstanding parts of the heel member, the heel member constituting two 70 75 80 pivotally connected arms.

5. An ice creeper of the class described comprising a member adapted to underlie the sole portion of a boot or shoe, a member adapted to underlie the heel portion of such footwear, both of said members having parts extending up on the opposite sides of the footwear, side members connecting said parts, retaining means coacting with the upstanding parts of the sole member, and retaining means 85 90 95 coacting with the upstanding parts of the heel member, said last named retaining means being also engaged with the sole member, said sole member constituting a toggle structure, said heel member constituting two pivotally connected arms adjustable horizontally.

6. An ice creeper comprising a toggle member adapted to underlie the sole portion of a boot or shoe, oppositely disposed arms carried by the toggle member and terminating in upstanding parts to overlie the opposite sides of the footwear, retaining means coacting with said upstanding parts, a heel member comprising two pivotally connected plates adapted to underlie the heel of the footwear, 100 said plates having upstanding arms for placement at opposite sides of the footwear, side members connecting the upper portions of the arms of the plates and the upstanding parts of the arms carried by the toggle member, and a strap freely engaged with the upper portions of the arms of the heel member and also freely engaged with the inner portion of the toggle member, said strap being adapted for securing over the instep of 105 110 115 the footwear.

7. An ice creeper comprising a toggle member adapted to underlie the sole portion of a boot or shoe, oppositely disposed arms carried by the toggle member and terminating in upstanding parts to overlie the opposite sides of the footwear, retaining means coacting with said upstanding parts, a heel member comprising two pivotally connected plates adapted to underlie the heel of the footwear, 120 125 said plates having upstanding arms for placement at opposite sides of the footwear, side members connecting the upper portions of the arms of the plates and the upstanding parts of the arms carried by the toggle member, a 130

strap freely engaged with the upper portions of the arms of the heel member and also freely engaged with the inner portion of the toggle member, said strap being adapted for 5 securing over the instep of the footwear, and a member having its extremities connected to the arms of the heel member and adapted to straddle the heel portion of the footwear from the rear.

10 In testimony whereof I hereunto affix my signature.

JOHN E. OSTRANDER.
